(57) **CLAIM**

The ornamental design for a beverage dispenser with hose, as shown and described.

DESCRIPTION

FIG. 1 is a top, front, right side perspective view of a beverage dispenser with hose showing our new design; FIG. 2 is a front elevation view thereof; FIG. 3 is a right side elevation view thereof; FIG. 4 is a top plan view thereof; FIG. 5 is a rear elevation view thereof; FIG. 6 is a left side elevation view thereof; FIG. 7 is a bottom plan view thereof; FIG. 8 is a top, rear, left side perspective view thereof; and, FIG. 9 is a left side elevation view of the beverage dispenser with hose, shown with the hose connected to a gas tank. The dash-dash broken lines shown in FIGS. 1-8 represent portions of the beverage dispenser with hose that form no part of the claimed design. The additional dash-dash broken lines shown in FIG. 9 represent environmental matter and form no part of the claimed design. The short dash-long dash broken lines define boundaries of the claimed design and form no part of the claimed design.
